ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

METHOD AND APPARATUS FOR CASTING CERAMIC PIECES.

Application filed July 2, 1926. Serial No. 120,091.

This invention relates to the manufacture of ceramic articles by the casting method and has for its object the provision of a method and apparatus for casting such articles which will permit the formation of articles with this method which could not heretofore be so manufactured and which will form articles of a superior nature and which will permit more convenient, economic and efficient operation than has heretofore been possible. Other objects of the invention would appear from the following description.

The invention is exemplified by the combination and arrangement of parts and by the steps of the process described in the following specification and illustrated in the accompanying drawings.

In the drawings
20 The figure is an elevation of one-half of a mould showing the formed piece and core in section.

In the casting method of forming ceramic articles the slip, consisting of the ceramic material, mixed with water, is placed in a porous mould commonly made of plaster of paris, and the ceramic material permitted to be deposited on the inner surface of the mould as the water is absorbed by the wall 30 of the mould.

The excess of water on the inner surface of the cast articles over that in the outer portion tends to cause the articles to crack in drying or warp in drying or firing.

35 The present method tends to equalize the water in the inner and the outer portions of the deposited layer and permit the forming of articles on a commercial basis much more economically. In general, the method 40 consists of using a flexible core which can be withdrawn. This core may be made in a variety of materials. One method is to use a rubber core which may be supported on a mandrel or a supporting structure.

45 After the piece is cast tension on the rubber member causes it to stretch and reduce in diameter, thus permitting the removal of the core. Where intricate or delicate parts are formed, the core may be allowed to remain in the piece until drying or hardening is carried to the point where the core can be removed without endangering the piece. In this case, it is necessary that the core be such that it will deform as the ware shrinks

in drying without producing a stress which will cause cracking. The surface of the core also aids in the building up and permits the filling of the slip in at points so that a solid mass is built up without internal defects. The core may be removed and used repeatedly. Frequently recesses or contours can be formed by the core which would otherwise require considerable work in the forming. A core of the above type may also be used for reducing excess material, thus effecting a saving in the material in some cases. The elimination of material in the cast piece at certain points may also permit the forming of a piece which would not otherwise be possible owing to the shrinkage or firing stresses.

The core may be made up in several different ways to cheapen its cost, to insure accuracy or to permit its removal. In some cases, the core may be made entirely out of rubber or material which will deform easily. In other cases, the outer layer of the core may be backed up with wax or other material which may be melted out or dissolved after the piece is formed. Where desired, the core may be relatively thin and after the piece has sufficiently formed, it may be extended or inflated with air, oil or water so that it will press upon the casting slip on the inner face and squeeze out the surplus water, tending to equalize the inner surface with the outer.

55 The figure shows half the mould with a section through the bushing and core used for forming the inner surface of the cast piece. The outside of the piece is formed by the porous mould 11, the two halves of the mould being clamped together by plates 13 with bolts through holes 14 or by other suitable means. Dowels 15 register with corresponding holes in the other half of the mould so that the two parts will register.

In the figure the core is made up in three parts. A main supporting member 16 forms the inner part of the core and also serves as a feed in pipe. Adjacent to member 16 is a layer of material 17 and 18. This material may be wax or may be a rubber tube, it only being essential that the material may be readily removed by melting or drawing out. Covering the members 17 and 18 and also a portion of the member 16 are envelopes 19 and 20. The members 19 and

20 have the shape desired on the inside of the bushing or article 21 to be formed. In forming a piece, the central member 16 with the forming cores or envelopes 19 and 20 together with the filling members 17 and 18 are placed in half the mould. The tubular member 16 is provided with a flange 22 which registers with the mould so that the core forming the inside of the bushing is 10 maintained in proper relation to the outside. After the composite core has been made up and placed in half the mould the other half is placed over it and the two parts are clamped and held together. Where heavy 15 pressures are desired, it is usually necessary to back up the moulds with a plate 13. The vent 23 is opened and casting slip is allowed to flow up through the center of the supporting member 16. A slip is fed outward 20 through the holes 24 extending through the wall of the pipe 16 and through the surrounding core members. The piece 21 to be formed builds up owing to the absorption of water by the mould due to capillary attraction, and also by the forcing out of the 25 water where pressure is applied. The outer surface of the core members 19 and 20 maintains the desired contour regardless of the fact that there may be a tendency to build 30 up more rapidly in certain sections than in others. Considerable control can be obtained in the building up operation by placing the feed in holes 24 opposite the places which tend to form last, although it is not 35 essential that the holes be placed at these points in many cases.

The method has the advantage that a 40 minimum diameter of opening may be maintained and practically any contour regardless of the normal tendency of the slip to build up along other lines. One difficulty in forming pieces where solid cores are used is due to the fact that the piece may build 45 up and shut off the flow of slip to some section of the piece, before a dense piece is formed. This section is likely to crack in drying or cause a pocket due to greater shrinkage owing to the presence of a larger 50 percentage of water or owing to the fact that there may have been a forming of a 55 pocket owing to the lack of sufficient casting material reaching the particular point. Feeding at the proper points in the improved method may be obtained by placing 60 proper holes along the core or even by providing holes entering from the outside at points where the piece may be fed. A feed tube of this nature is shown at 25. The piece may be formed entirely from the outside or entirely from the core or by a combination of the two without affecting the scope of the invention. After the piece has been built up and it is not possible for slip to flow along the surface, a compact inner 65 surface will still be formed with the im-

proved method owing to the fact that the envelope 19 and 20 will expand from the pressure on the inside. This will tend to drive excess water out of any slip on the adjacent surface and cause a piece of more uniform density to be formed, thus reducing the danger of cracking during drying and eliminate warping. The supporting inner member 16 may be a tube with a few openings or may have a skeleton construction or 70 a number ports 26 which will permit the pressure on the inside to press the outer layers outward and compact the surface. Where the spacing members 17 and 18 are made of wax, the tube or center supporting member 16 is heated by either passing through steam, hot oil, or electrically or by other suitable means. This softens the layer 75 17 and 18 and permits the withdrawal of the members 19 and 20 or the removal of the member 16. Where the piece is placed in a warm place, the remaining wax 18 will then be soft enough to permit the yielding of the members 19 and 20 and take care of the deformation of the formed piece as it shrinks. 80 Another method of operation is to make the members 17 and 18 of rubber, making same of suitable shape. These may be in a single piece or in a number of pieces as desired. After the piece of ware is formed and half 85 of the mould is removed the center member and core may be used to support the piece and lift it from the mould. By pulling on the pieces 17 and 18, they can be readily withdrawn. This permits the removal of 90 the member 16 and the withdrawal of the forming core 19 and 20. Where these pieces are made of rubber, they may readily be removed and used repeatedly. If the rubber 95 is of the right composition, they may be stretched, which causes them to be reduced in diameter and thereby to be withdrawn very readily without harming the piece.

It is, of course, evident in many cases that the pieces 18 and 20 may be combined as well as the pieces 17 and 19. In some cases where the forming core has sufficient stiffness, the rigid supporting member 16 may be left out.

There are many articles which may be formed in this way. The use of the core makes the timing in the casting unnecessary, permits a more uniform density throughout the piece and permits the controlling of an inner contour which would not be possible in the ordinary casting method, except where the cores are of such shape that they may be readily removed. The method used permits the removal of a core without disturbing the piece which is not possible with the ordinary rigid core except for the simple shapes and for cores having considerable draft. The method consists essentially of having a core of sufficient rigidity to form the contour desired and which has sufficient flexibility so that it can be withdrawn, or,

if left in the piece allowed to contract without setting up undue stress owing to shrinkage of the piece. The flexibility of the core also makes it possible to thoroughly compact 5 the inner surface.

I claim—

1. The method of manufacturing ceramic articles comprising the steps of depositing plastic material from a slip about a yielding 10 core and removing the core from the formed piece.

2. The method of casting ceramic articles comprising the steps of arranging a yielding core within a porous mould, introducing 15 slip into the space between said core and mould to cause said space to be filled with deposited material from said slip, contracting said core and removing same from the piece formed by the deposit of the material 20 from said slip.

3. The method of casting ceramic articles comprising the steps of depositing material about a yielding core and permitting said material to dry, said core being compressed 25 during the drying process to prevent undue stress in the formed piece.

4. The method of casting ceramic articles comprising the steps of arranging a core of yielding material in a mould of porous material, introducing slip into said mould to 30 fill the space between said mould and core with material from said slip removing the formed piece from said mould and permitting said piece to dry with a portion of said 35 core in place, said core yielding to contraction of said formed piece during the drying operation.

5. The method of casting ceramic articles comprising the steps of arranging a core 40 within a mould, depositing material in the space between said core and mould after the core is in place in the mould and exerting pressure on the interior of said core to press said core against the deposited material.

45 6. The method of casting ceramic articles comprising the steps of arranging a yielding core within a porous mould, introducing slip into said mould to fill the space between said core and mould with material deposited 50 from said slip and introducing pressure on the interior of said core to press said core outwardly against the inner face of the material deposited in said mould, thus placing the material under pressure and expelling 55 water therefrom.

60 7. The method of forming ceramic articles comprising the steps of arranging a core comprising inner and outer core sections within a porous mould, depositing material between said core and mould and removing said core sections successively from said mould.

8. The method of forming ceramic articles

comprising the steps of arranging a sectional core having portions made of yielding material within a porous mould, introducing slip into said mould to fill the space between said core and mould with material deposited from said slip and removing a portion of said core from the formed piece 70 previous to drying thereof, the remaining portion of the core being permitted to yield to contraction of said piece in drying.

9. The method of forming ceramic articles comprising the steps of arranging a core of yielding material within a porous mould, introducing slip into said mould to fill the space between said core and mould with material deposited from said slip exerting pressure 75 on the interior of said core to compress the material deposited from said slip and expell excess moisture therefrom, removing the formed piece from the mould, contracting the core and removing the core from the formed piece. 80

10. A mould comprising an outer portion of porous material and a core of yielding material having a definite shape inherent in said core.

11. A mould comprising an outer portion 90 of porous material and a core having a central supporting portion and a covering of yielding material, the outer surface of said covering having inherently the contour of the interior of the article to be moulded. 95

12. A mould comprising an outer portion of porous material and a core having a central supporting section, an outer layer of yielding material and a removable section between said central supporting section and 100 outer layer.

13. A mould comprising an outer portion of porous material and a core having a hollow central support, an outer layer of yielding material and a removable section interposed between said central support and outer layer, the walls of said core being perforated to permit introduction of slip into the space between said core and the surrounding mould. 110

14. A mould comprising an outer portion of porous material and a central core, said outer portion and core, each having an opening therethrough for the introducing of slip into said mould. 115

15. A mould comprising an outer portion of porous material and a core having a central opening, the outer surface of said core being yielding, said core and outer portion having passages therein for the introducing 120 of slip into said mould.

In testimony whereof I have signed my name to this specification on this 29th day of June, A. D. 1926.

ARTHUR O. AUSTIN.
